(57) **CLAIM**

The ornamental design for a bottle, as shown and described.

DESCRIPTION

FIG. 1 is a front, perspective view of a bottle showing our new design;

FIG. 2 is a front view thereof, the rear view being identical thereto;

FIG. 3 is a side view thereof, the opposite side view being identical thereto;

FIG. 4 is a top view thereof; and,

FIG. 5 is a bottom view thereof.

The broken line showing of the pour spout is for illustrative purposes only and forms no part of the claimed design.
